(57) **CLAIM**

The ornamental design for outer end portions of a garment hanger, as shown and described.

DESCRIPTION

FIG. 1 is a perspective view of outer end portions of a garment hanger showing my new design;

FIG. 2 is a front elevational view thereof;

FIG. 3 is a back elevational view thereof;

FIG. 4 is a first side elevational view thereof;

FIG. 5 is a second side elevational view thereof;

FIG. 6 is a top plan view thereof; and,

FIG. 7 is a bottom plan view thereof.

The broken lines shown in the drawing disclosure are for illustrative purposes only and form no part of the claimed design.
